The ornamental design for a pediment for walls, as shown and described.

DESCRIPTION

FIG. 1 is a front elevational view of a pediment for walls showing my new design, the rear of said panel being plain and unornamented;

FIG. 2 is an end elevational view thereof, the opposite end being a mirror image thereof; and,

FIG. 3 is a cross-sectional view taken along line 3—3 of FIG. 1.

FIG. 2

FIG. 3
